UNITED STATES PATENT OFFICE.

VICTOR EMANUEL FERMIER, OF FORNEY, TEXAS.

TOY.

1,295,292.

Specification of Letters Patent. Patented Feb. 25, 1919.

Application filed August 1, 1918. Serial No. 247,809.

To all whom it may concern:

Be it known that I, VICTOR EMANUEL FERMIER, a citizen of the United States, and a resident of Forney, in the county of Kaufman and State of Texas, have invented certain new and useful Improvements in Toys, of which the following is a specification.

My invention is an improvement in toys, and relates to toys having movable figures, 10 wherein a base is provided having thereupon two figures, one of which is hinged to take an upright or reclining position, and the other has a movable member spring operated to strike and knock down the first named 15 figure and wherein releasable means is provided for restraining the operation of the striking member.

In the drawing:

Figure 1 is a perspective view of the toy 20 in set position,

Fig. 2 is a top plan view,

Fig. 3 is a bottom plan view with the lower disk removed,

Fig. 4 is a vertical section with the figure 25 in reclining position,

Fig. 5 is a horizontal section at the shoulder of one of the figures, and

Fig. 6 is a section on the line 6—6 of Fig. 2, looking in the direction of the arrow adjacent to the line.

In the present embodiment of the invention, a base is provided of circular form consisting of an upper disk 1 and a lower disk 2, the said disks being secured together 35 in spaced relation, by means of spacing blocks 3 which are arranged at the peripheries of the disks.

Two figures 4 and 5 are mounted upon the topmost disk 1, the figure 4 having the right 40 foot connected to the topmost disk by means of a hinge 6 to permit the figure to take the upright position of Fig. 1, or the reclining position of Fig. 4.

A flexible member as for instance a cord 45 has one end connected to the left foot of the figure 4 and this cord passes down through an opening 8 in the topmost disk 1 and to a connection with a lever 9 to be described, the arrangement being such that when the lever 50 is swung in one direction the figure will be moved into vertical or upright position.

The figure 5 is rigidly connected to the disk 1 in any suitable manner, and the right arm 9a thereof is hinged to the figure to 55 swing in a horizontal plane. The pintle 10 of the hinge connection extends downwardly

through an opening in the topmost disk 1, to a rigid connection with the wheel 11 which is arranged between the disks, and the lever 9 before mentioned extends radially 60 from the said wheel, being secured thereto in any suitable or desired manner.

A coil spring 12 is connected at one end to the lever 9 intermediate its ends, and adjacent to the connection of the cord 7, which 65 is also intermediate the ends of the lever, and the other end of the spring is connected to a pin 13 on one of the disks. This spring normally acts to swing the lever and the arm 9 in the direction of the other figure 4 70 to cause the hand of the arm to slap the face of the figure 4, and knock it into the position of Fig. 4.

The lever 9 at the end of its movement under the influence of the spring 12 engages 75 a stop 14 similar to the blocks 3 and arranged between the disks 10, and at the end of its movement in the other direction the lever is engaged by a releasable trip or trigger 15. This trip or trigger is pivoted 80 intermediate its ends in a slot in the upper disk 1, and it has at one end a foot plate which extends above the disk, and at the other a catch which engages over the lever to hold it from movement under the impulse 85 of the spring.

In operation, the lever 9 which extends but a short distance beyond the peripheral edges of the disks 1 and 2 is moved from its engagement with the stop block 14 to the 90 position of Figs. 2 and 3, where it is engaged with the catch of the trip, and is held from movement under the influence of the spring by the catch. This movement of the lever not only tensions the spring, and 95 moves the right arm of the figure 5 into withdrawn or set position, but also swings the figure 4 into vertical or upright position. To cause the figure 5 to strike, the trip is operated to release the lever. The spring 100 12 immediately swings the lever and causes the arm 9a to swing toward the figure 4, and the hand thereof will strike the cheek of the figure 4 and will upset the said figure as shown in Fig. 4.

I claim:

1. A device of the character specified, comprising a base, a plurality of figures supported on the base, one of said figures being hinged to the base to stand upright or 110 to recline thereon, the other figure having a hinged arm mounted to swing into and

out of engagement with the first named figure to overset the same, the pintle pin connecting the said arm to the body of the figure extending downwardly into the base and 5 having a lever secured thereto, a spring connected with the lever and acting normally to move the hinged arm toward the other figure, a flexible connection between the first named figure and the lever for moving the 10 first named figure into upright position when the lever is moved against the resistance of the spring, a stop for limiting the movement of the lever under the influence of the spring, and a releasable trip for holding the lever 15 from movement under the influence of the spring.

2. A device of the character specified, comprising a base, a figure hinged to the base to stand upright or recline thereon, a second 20 figure mounted on the base and having a hinged portion mounted to swing and engage the first named figure to overset the same, a spring for moving said movable portion toward the first named figure, a lever

for moving the movable portion away from 25 said first named figure, and releasable trip means for holding the lever against the resistance of the spring, and a flexible connection between the first named figure and the lever for moving the said figure into an 30 upright position when the spring is under tension.

3. A device of the character specified, comprising a base, a figure hinged thereto to recline on the base or stand erect, a second 35 figure having a portion mounted to swing and strike the first named figure, a spring normally moving said portion into operative position, a releasable trip for restraining the action of the spring, and a connection between the hinged figure and the movable portion for moving the first named figure into upright position when the spring is 40 under tension.

VICTOR EMANUEL FERMIER.
